(Continued)

(**) Term: **15 Years**

Primary Examiner — Jae Liang

(21) Appl. No.: **29/814,208**

Assistant Examiner — Ji Sun Yoon

(22) Filed: **Nov. 4, 2021**

(74) Attorney, Agent, or Firm — Janeway Patent Law PLLC; John M. Janeway

(57) **CLAIM**

The ornamental design for a lid, as shown and described.

DESCRIPTION

(63) Continuation of application No. 29/741,090, filed on Jul. 9, 2020, now Pat. No. Des. 946,346.
(51) **LOC (14) Cl.** **07-99**
(52) **U.S. Cl.**
USPC **D7/396.2**; D7/392.1

See application file for complete search history.

FIG. 1 is a perspective view of a lid showing my new design.
FIG. 2 is another perspective view of the lid shown in FIG. 1.

FIG. 3 is a front, elevation view of the lid shown in FIGS. 1 and 2.
FIG. 4 is a rear, elevation view of the lid shown in FIGS. 1 and 2.

FIG. 5 is a left, elevation view of the lid shown in FIGS. 1 and 2.
FIG. 6 is a right, elevation view of the lid shown in FIGS. 1 and 2.

FIG. 7 is a top, plan view of the lid of the cup and lid shown in FIGS. 1 and 2; and,

FIG. 8 is a bottom, plan view of the lid of the cup and lid shown in FIGS. 1 and 2.

The broken lines in FIGS. 1, 2 and 7 are for the sole purpose of showing portions of the lid, and do not form a part of the claimed design.
